(57) **CLAIM**

The ornamental design for a display screen with an animated graphical user interface, as shown and described.

DESCRIPTION

FIG. 1 is a front view of the first image of a display screen with an animated graphical user interface showing a first embodiment of our new design;

FIG. 2 is a front view of a second image of the first embodiment;

FIG. 3 is a front view of a third image of the first embodiment;

FIG. 4 is a front view of a fourth image of the first embodiment;

FIG. 5 is a front view of a fifth image of the first embodiment;

FIG. 6 is a front view of the first image of a display screen with an animated graphical user interface showing a second embodiment of our new design;

FIG. 7 is a front view of a second image of the second embodiment;

FIG. 8 is a front view of a third image of the second embodiment;

FIG. 9 is a front view of a fourth image of the second embodiment;

FIG. 10 is a front view of a fifth image of the second embodiment;

FIG. 11 is a front view of the first image of a display screen with an animated graphical user interface showing a third embodiment of our new design;

FIG. 12 is a front view of a second image of the third embodiment;

FIG. 13 is a front view of a third image of the third embodiment;

FIG. 14 is a front view of a fourth image of the third embodiment;

FIG. 15 is a front view of a fifth image of the third embodiment;

FIG. 16 is a front view of the first image of a display screen with an animated graphical user interface showing a fourth embodiment of our new design;

FIG. 17 is a front view of a second image of the fourth embodiment;

FIG. 18 is a front view of a third image of the fourth embodiment;

FIG. 19 is a front view of a fourth image of the fourth embodiment; and,

FIG. 20 is a front view of a fifth image of the fourth embodiment.

The broken line drawing of a display screen in all views forms no part of the claimed design. The broken line showing of portions of the animated graphical user interface form no part of the claimed design.

The appearance of the transitional image sequentially transitions between the images shown in FIGS. 1-5 of the first embodiment, FIGS. 6-10 of the second embodiment, FIGS. 11-15 of the third embodiment and FIGS. 16-20 of the fourth embodiment. The process or period in which one image transitions to another image forms no part of the claimed design.

1 Claim, 20 Drawing Sheets
